UNITED STATES PATENT OFFICE.

JOHN W. BRADY, OF NEODESHA, KANSAS, ASSIGNOR OF ONE-HALF TO ELIAS M. WALKER,
OF NEODESHA, KANSAS.

TRACK-SANDER.

No. 909,056.

Specification of Letters Patent.

Patented Jan. 5, 1909.

Application filed January 21, 1908. Serial No. 411,992.

To all whom it may concern:

Be it known that I, JOHN W. BRADY, a citizen of the United States, residing at Neodesha, in the county of Wilson and State of Kansas, have invented new and useful Improvements in Track-Sanders, of which the following is a specification.

This invention relates to track sanding devices and one of the principal objects of the invention is to provide simple and efficient means for depositing sand upon either track at the sides of a locomotive by means of air connections leading to the locomotive cab.

Another object of the invention is to provide a sanding device into which the air pipe leading from the auxiliary reservoir of the truck system to the sanding device shall have no abrupt corners to obstruct the air in operating the device, and wherein the air pipe nozzle is arranged below the sand outlet thereby preventing the moisture from the air passing through the nozzle coming in contact with the sand opening.

To these ends the invention resides in the novel construction of elements and their arrangement in operative combination herein-after fully described and claimed.

Figure 1 is an elevation of a sand dome of a locomotive, showing the same provided with my improvement, and, Fig. 2 is a detail vertical section of my improvement.

Referring to the accompanying drawings, the numeral 1 designates a casing or dome for containing sand, said casing being provided with a suitable cover 2, and the said dome being positioned upon the top of the locomotive boiler 3. Air pipes 4 leading from the auxiliary reservoir within the cab pass through fittings 5 secured to the wall of the casing 1. Each of the air pipes 4 is provided with a suitable outlet pipe 6 positioned upon each side of the dome 1 in a manner similar to that described in my patented device Number 877,828. These outlet pipes 6 project a suitable distance away from the dome and are provided with a right angular extension 7 having an enlargement or collar 8 at its extremity. A union 9 is provided upon the vertical offset of the outlet pipe and is adapted to engage the collar 8 and a nozzle 10. This nozzle 10 is provided with a suitable shoulder 11 and a screw threaded portion projecting downwardly from said shoulder and adapted for engagement with the upper internal threads of a T

coupling 12 the lower threaded opening of the coupling 12 is provided with suitable threads adapted for the engagement of the threaded portion of the outlet pipe 13. The offset member 14 of the coupling 12 is adapted to extend upwardly at an angle and towards the dome 1. The mouth of the T coupling 12 is adapted to lie in a plane below the reduced mouth of the nozzle 10.

The sand outlet or hood 15 is provided with a threaded extension 16 adapted for the reception of the shank 17 upon the exterior of the dome 1. The shank 17 is provided with an annular shoulder 18, and a union 19 secured upon the shank 17 is adapted to engage the shoulder of the threaded extremity 20 of the offset 14. A suitable lock nut 21 is provided upon the threaded portion of the sand outlet upon the interior of the dome and is adapted to retain the outlet hood in secure engagement with the casing.

The hood, comprising the sand outlet employed with my device is constructed of a rounded top and has its bottom cut away a suitable distance to provide an outlet mouth 22.

The operation of my device is as follows:— It will be understood that the sand in the casing 1 will not be fed through the outlet pipes excepting when air is projected through the air pipes and through the nozzle 10. Whenever it is desired to sand the tracks, the engineer opens the valve to project air through the pipes 4 and 6, and the air passes through the nozzle at right angles to the sand pipe connection which draws the sand through the said pipe and projects it through the sand pipes 13 to the track.

It will be noted that by the construction of the T 12 having the air nozzle 10 and its offset member 14 arranged away from the air nozzle and at an angle so as to position the sand outlet pipe above the nozzle, the point of the inflow of air is below the sand outlet opening and thus all moisture from the air passing through the nozzle is prevented from coming in contact with the sand outlet opening.

Having thus described the invention what is claimed as new is:—

1. A sanding device comprising a casing or dome, air pipes leading into the casing or dome and out through the sides thereof, nozzles fitted to said air pipes, said nozzles being fitted in couplings having an offset member

extending upwardly away from the nozzle so as to have its inner passage above the outlet of the nozzle, an outlet pipe connected to the vertical member of the coupling and a sand outlet connected to the offset member and extending within the dome.

2. In a sanding device, a dome, air pipes connected to said dome and extending upwardly upon opposite sides thereof, a nozzle connected to the outlet pipes, a coupling connected to said nozzle, said coupling comprising a vertical member and an offset member,

the offset member being arranged at an angle to the vertical member so that its passage will be above the outlet of the nozzle, a sand outlet connected to the offset member, said outlet having a rounded deflector provided with a reduced mouth upon its lower face.

15 In testimony whereof I affix my signature in presence of two witnesses.

JOHN W. BRADY.
